UNITED STATES PATENT OFFICE.

CARL H. GUSTAFSON, OF ALBERT CITY, IOWA.

RADIATOR GUARD.

Application filed February 27, 1928. Serial No. 257,270.

The object of my invention is to provide a radiator guard of simple, durable, and comparatively inexpensive construction.

A further object of my invention is to provide a radiator guard especially adapted for tractors and particularly designed to prevent corn stalks from coming in contact with the radiator.

Still a further object is to provide the guard with the center thereof projecting forwardly from the sides so that as the tractor advances, the guard is at an angle relative to the line of advance and will push any corn stalks in front of the radiator over to the side.

Still a further object is to provide the guard in the form illustrated so that it is a considerable distance from the radiator itself and the suction of the radiator therefore will not have so much effect on the screen of the guard to cause leaves and trash to adhere thereto on account of the suction formed by the radiator fan.

Still a further object is to provide the guard in the form of two members covered with screen or perforated metal and to hinge these members at their outer side edges to the sides of the radiator so that they can be opened up and when in open position will not interfere with the operator when cranking the tractor.

Still a further object is to provide a bottom member for the guard to prevent stalks of corn from extending upwardly between the guard and the radiator and coming in contact with the radiator.

With these and other objects in view, my invention consists in the construction, arrangement and combination of the various elements of my radiator guard whereby the objects contemplated are attained, as herein-after set forth, pointed out in my claims and illustrated in the accompanying drawings, in which:

Figure 1 is a plan view of the front portion of a tractor illustrating my improved radiator guard attached thereto.

Figure 2 is a front elevation of the guard itself.

Figure 3 is a perspective view of one half of the guard.

Figure 4 is an enlarged detail sectional view on the line 4—4 of Figure 2 illustrating a latch for the two halves of the guard; and

Figure 5 is an enlarged sectional view on

the line 5—5 of Figure 1 illustrating a portion of the latch.

On the accompanying drawings I have used the reference numeral 10 to indicate generally a tractor. The tractor radiator is indicated at 12 and is usually formed with flanges 14 adjacent its top and bottom ends. The flanges 14 divide the radiator into three separate parts and these parts are held together by bolts 16.

65 The radiator guard itself comprises a pair of guard members A and B each consisting of a frame 18, a screen or perforated sheet metal covering 20 and bottom member 22. The frame 18 may be formed of any suitable 70 material and in the present instance I have used angle iron. The screen 20 is preferably a medium mesh screen so as to allow for admission of air without interfering with the suction of the fan and yet preventing the entrance of corn stalks, leaves, trash, etc. The bottom member 22 may be formed of sheet metal.

75 In order to keep the guard members A and B in alignment without sagging, I provide 80 brace members 24 at the corners of the frame 18. The members A and B are hinged to the radiator 12 in the following described manner.

85 A pivot rod 26 is supported at one end of each guard member A and B. The rod 26 may extend through flanges of the frame 18 and be riveted in position or provided with a head on one end and a nut on the other end. A pair of straps 28 are rotatably mounted 90 on each rod 26 and the lower strap 28 is held against upward movement on the rod by a collar or the like 30. The straps 28 are rigidly mounted on flanges 14 of the radiator 12 by the bolts 16.

95 From the foregoing description it will be obvious that the guard members A and B are pivotally mounted relative to the radiator 12. The purpose of this construction is so that these members may assume the full line position illustrated in Figure 1 of the drawings which is the normal position for them or may assume the dotted line position whereby the tractor may be conveniently cranked by the operator.

100 The member B is provided with an angle 31 adapted to coact with the free edge of the member A. For latching the members A and B together I provide latch devices C each comprising a U shaped strap 32, latch 110

pin 34 and spring 36. The strap 32 is fastened to the angle 31. The latch pin 34 is provided with a head 38 of irregular shape and the flange 18^a of the member A is provided with an opening 40 of similar shape. There is, of course, an opening 40 for each of the latch devices. A ring 42 is formed on the pin 34 for convenience in manipulating the latch.

10 In Figure 5 the latch is illustrated in latched position. By turning the head 38 to register with the opening 40 the latch pin may be withdrawn from the angle 18^a and the members A and B may be opened. In 15 latched position the spring 36 causes the head 38 to pull on the flange 18^a for holding the two members A and B together.

19 The guard members A and B may be provided with top members 22^a if so desired. 20 The top members 22^a are triangular in shape similar to the bottom members 22 and prevent the falling of corn stalks, leaves etc., down behind the guard members and onto the bottom members 22.

25 The bottom members 22 are preferably formed with notches 23 which form an opening when the device is in closed position as illustrated in Figure 1. This opening is designed to receive the crank 11 of the tractor for holding it in raised position when the guard members are closed. In order to do this after cranking the tractor the operator turns the crank to an upstanding position 30 and holds it there while closing the guard members A and B. This effectively holds the 35 crank in raised position and also prevents the crank being pushed back into gear with the engine when an object strikes it.

From the foregoing construction it will be 40 apparent that I have provided a radiator guard which serves to force the corn stalks to the sides of the tractor as the tractor is being driven across the field. The screen 20 is located at a considerable distance from 45 the radiator 12 and effectively prevents the collection of trash and leaves on the screen itself.

Some changes may be made in the construction and arrangement of the parts of my device without departing from the real spirit 50 and purpose of my invention, and it is my intention to cover by my claims, any modified forms of structure or use of mechanical equivalents, which may be reasonably included within their scope.

I claim as my invention:

1. The combination with a radiator of a 60 radiator guard comprising a pair of guard members each having one edge secured to a side of the radiator, said members extending forwardly and converging and having their free edges secured together and a bottom member between the lower ends of said guard members and said radiator.

65 2. The combination with a radiator of a

radiator guard comprising a pair of guard members each having one edge pivoted to a side of the radiator, said members extending forwardly and converging and having their free edges detachably connected together. 70

3. The combination with a radiator of a radiator guard comprising a pair of guard members each having one edge pivoted to a side of the radiator, said members extending forwardly and converging and having their free edges detachably connected together and a bottom member secured to each of said guard members. 75

4. A radiator guard comprising a pair of perforated guard members hinged to the side 80 edges of a radiator and means on the free edges of said members for detachably securing said edges together.

5. A radiator guard comprising a pair of perforated guard members hinged to the side 85 edges of a radiator and means on the free edges of said members for detachably securing said edges together, said members extending forwardly from the radiator and converging toward each other to form a pointed 90 guard.

6. A radiator guard comprising a pair of perforated guard members hinged to the side edges of a radiator and means on the free 95 edges of said members for detachably securing said edges together, said members extending forwardly from the radiator and converging toward each other to form a pointed guard and an imperforate bottom member secured to each of said guard members and adapted to close the space between the bottom of the guard and the bottom of 100 the radiator when the guard members are in closed position.

7. A radiator guard comprising a pair of 105 perforated guard members hinged to the side edges of a radiator and means on the free edges of said members for detachably securing said edges together, said members extending forwardly from the radiator and converging toward each other to form a pointed 110 guard and an imperforate bottom member secured to each of said guard members and adapted to close the space between the bottom of the guard and the bottom of the 115 radiator when the guard members are in closed position, said bottom members being notched whereby said notches form an opening when the device is in closed position through which the crank may extend.

8. The combination with a radiator of a radiator guard comprising a pair of guard members each having one edge pivoted to a side of the radiator, said members extending forwardly and converging and having their free edges detachably connected together and a bottom member secured to each of said guard members, said bottom members having means for supporting a crank when the device is in closed position. 120

9. The combination with a radiator of a radiator guard comprising a pair of guard members each having one edge pivoted to a side of the radiator, said members extending forwardly and converging and having their free edges detachably connected together and bottom and top members secured to each of said guard members.

10. A radiator guard comprising a pair of perforated guard members hinged to the side edges of a radiator and means on the free

edges of said members for detachably securing said edges together, said means comprising a pin mounted in one member, an irregular shaped opening in the other member, an irregular shaped head on said pin to extend through said opening and resilient means on said pin to constrain the pin to move in one direction. 15

Des Moines, Iowa, February 15, 1928.

CARL H. GUSTAFSON.
